(57) CLAIM

The ornamental design for a walking shoe, as shown and described.

DESCRIPTION

FIG. 1 is a front elevational view of the walking shoe showing my new design;

FIG. 2 is a rear elevational view of the walking shoe thereof;

FIG. 3 is a right side elevational view of the walking shoe thereof;

FIG. 4 is left side view of the walking shoe thereof;

FIG. 5 is a top plan view of the walking shoe thereof; and,

FIG. 6 is a bottom plan view of the walking shoe thereof. The broken line showing of the name "Walk For God" is included for the purpose of illustrating and forms no part of the claimed design.
